RECOVERY OF PENTOSES AND HEXOSANS
FROM WOOD LIQUORS

Horace E. Hall, Lyle, Tenn., and Lester L. Coleman, Wilmington, Del., assignors to Masonite Corporation, Laurel, Miss., a corporation of Delaware

No Drawing. Application March 31, 1944,
Serial No. 529,037

6 Claims. (Cl. 195—11)

1

This invention relates to enzymatic hydrolysis of non-cellulosic carbohydrate anhydrides, or sugar precursors, i. e., materials from which sugars may be formed, and more particularly to the selective enzymatic hydrolysis of precursors of pentose sugars.

It further relates to a process including the utilization of selective enzymatic hydrolysis upon solutions containing mixtures of sugar precursors, whereby the precursors of pentose sugars are hydrolyzed to pentose and the remaining sugar precursors are unaffected and can be separately recovered.

The practice of the process will be described upon wood liquors derived from wood or woody ligno-cellulose materials which may be obtained, as by expression or washing, from fiber produced by subjecting wood chips to the hydrolyzing action of high pressure steam in a gun, such as described in U. S. Patent 1,824,221 to Mason, followed by explosive discharge from the gun. Such a liquor is described in U. S. Patent No. 2,224,135 to Boehm.

The wood liquor obtained as described contains materials produced from hemicelluloses by the high-pressure steam treatment and which are soluble or dispersible in water. From these materials hexose and pentose sugars may be formed, and while such precursors of hexose and pentose may be in part polyuronides as well as polysans, they are herein referred to for convenience as hexosans and pentosans. The liquor also contains soluble or dispersed tars, some free sugars, acetic acid, formic acid, soluble or dispersed lignin or lignin-degradation products, astringents, and various other materials.

One mode of utilizing only the pentose precursor material contained in such wood liquors is described and claimed in the application for U. S. patent of R. M. Boehm, Ser. No. 352,399, now Patent 2,369,655. This consists in subjecting the liquor, preferably in concentrated form, to severe hydrolysis in the presence of a mineral acid, carried to such extent that a high yield of furfural and the like products are obtained. Such relatively harsh hydrolysis treatment degrades the hexose precursors or hexoses, as by caramelization, tar formation and the like, to the extent of making them unfit for subsequent fermentation or like treatment.

2

The present invention avoids such degradation of hexose precursors by providing a process to effect a separation of the sugar precursors, sugars, etc., before the pentose sugars and/or pentose precursors are subjected to such severe mineral acid hydrolysis treatment.

One object of the invention is to provide a process for effecting a selective enzymatic hydrolysis of pentosan material to pentose sugars in a mixture containing pentosans and hexosans, thereby permitting the hexosans to be removed.

A further object is to provide a process whereby both the hexosan content and pentosan content of a solution containing hexosans and pentosans can be utilized by effecting an enzymatic hydrolysis of the pentosans and thereby converting the solution to a solution containing mixtures of pentoses and substantially unchanged hexosans, and the hexosans can be removed from the latter solution.

In setting forth the practice of the invention on the wood liquor described above, two embodiments will be presented for purposes of illustration. In one, such liquor is used without previous purification treatment. In the other, liquor is used from which most or all of the constituents other than pentosans and hexosans have been removed.

When the liquor to be treated according to the process of the present invention consists of a mixture of hexosan and pentosan material, along with other materials such as tars, organic acids, astringents, etc., as in the case of wood liquors above referred to, it may be subjected to enzymatic hydrolysis without preliminary treatment to eliminate the tars, etc. The enzyme material which has been found best adapted for this purpose is that resulting from the action of the mold *Aspergillus niger*. Such material may be supplied as by adding bran containing same to the solution. The enzymatic hydrolysis treatment is carried out at suitably low temperatures in the range of about 50°—60° C., which has been found best adapted to secure high yields of pentose. The preparation of the enzyme and hydrolysis treatment therewith will be further described below.

With use of *Aspergillus niger* enzymes as the hydrolyzing agent, a very effective conversion of pentosan material to pentose can be obtained.

This may be instanced by hydrolysis effects obtained with two batches of liquor which had been produced as above described from pine wood and gum wood respectively. The solid content of such liquors was approximately 4 parts in 100. Upon hydrolyzing the liquor from pine wood with the *Aspergillus niger* enzyme, 75% of the pentosans were hydrolyzed, with no evidence of hydrolysis of the hexosans. In the case of gum wood 80% of the pentosans were hydrolyzed.

After the hydrolysis treatment has been completed, the liquor is a solution in water of pentoses and hexosans, and containing extraneous materials, as tars and the like. After removal of the bran, as by filtration, the hexosans may be separated from the pentoses by addition, to the solution of an oxygenated water-miscible organic liquid, as for example acetone, a mixture of acetone and isopropyl ether, dioxane, or the lower aliphatic alcohols, as methanol or ethanol. As a result of this treatment, the hexosans are apparently dehydrated and are precipitated, and they can be filtered out while the pentoses remain in solution. The precipitated hexosan material may be washed with acetone or the like solvent to remove any tars, etc., which have been carried down with the hexosan material, and may subsequently be used for any desired purpose, as for example, fermentation to produce organic acids and solvents.

After recovering the additive precipitating agent materials for re-use, which can be done, for example, by low temperature distillation, the remaining liquor may be used for making furfural by hydrolyzing the pentose in presence of mineral acid. Thus destruction of hexosans can be avoided and precursors of both hexose and pentose may be utilized to advantage.

While the organic additive material may satisfactorily be used in amounts ranging from 2 to 7 volumes to one volume of solution, best results have been obtained with addition of about 4 volumes of the organic additive or precipitating agent material to one volume of solution. While several organic additive materials give satisfactory results, optimum precipitation has been obtained when using a mixture of acetone and isopropyl ether wherein the acetone is present in the amount of about 4 volumes to about one volume of isopropyl ether, although a range of volume ratios, as for example, 3 to 8 volumes of acetone to one volume of isopropyl ether gives satisfactory results. The quantity of additive precipitating agent material to be used can be reduced by concentrating the liquor, preferably after the enzymatic hydrolysis, as for example, concentrating to a solid content ranging up to about 50%.

Before adding the water-miscible organic material to be used for precipitation of the hexosan material, it is preferable to adjust the pH of the solution. The best results have been obtained with adjustment of the pH to about 5.5. However, a range of pH from about 2 to 11 is permissible.

The precipitation may be accelerated, if desired, by addition to the hexosan containing solution of a minor proportion, as about 1% to 5% of a suitable electrolyte, preferably an electrolytic salt, as for example, aluminum sulfate, the percentage being based on weight of solution.

When it is desired to obtain the pentose sugars in a relatively pure state, and free from the tars and other materials contained in wood liquor, it is preferable to subject the sugar-precursor

containing liquor to precipitation treatment before subjecting it to enzymatic hydrolysis. The precipitation of both hexosans and pentosans can be effected by addition to the liquor of water-miscible organic materials as above described in connection with precipitation of the hexosans. This treatment will allow recovery of relatively pure hexosans and pentosans which may be dissolved in water and subjected to the above described enzymatic hydrolysis treatment. After the enzymatic hydrolysis treatment, the hexosans can readily be separated from the pentose sugars by the previously described precipitation procedure, and the separated components can be treated as desired.

Another mode of eliminating tars, etc., from the wood liquor is that of using such materials as dried blood, cetyl amine, and the like to precipitate these undesirable components.

When this procedure using cetyl amine, dried blood or the like is followed, the solution which is obtained as a filtrate is ready to be subjected to the hydrolyzation treatment with *Aspergillus niger* or like enzymes, and such treatment together with the remainder of the process proceeds as previously described.

With use of *Aspergillus niger* enzyme for effecting hydrolysis, this enzyme material is preferably prepared by moistening wheat bran and inoculating the mass with a few spores of the mold *Aspergillus niger*. Mold taken from moldy bread is suitable. The container is shaken occasionally to prevent limping and uneven growth, and within about 48 to 72 hours the growth has proceeded to a point where rapid sporulation is evidenced. At this point maximum amounts of enzyme are available and the moldy bran is spread to dry at room temperature. When the material has been air-dried, the bran containing the *Aspergillus niger* enzymes is ready for use in the hydrolysis treatment.

The enzyme material is added to the liquor containing pentosans and hexosans in relatively small quantities and under mild conditions, as for example, the moldy bran is added in quantities of about 5 to 10 parts to 1000 parts by weight of liquor. The temperature should be maintained at about 50° to 60° C. and the liquor being treated should be agitated occasionally during the hydrolyzing treatment which requires about 24 to 48 hours.

The extent of the hydrolysis may be judged by the degree of coagulation of the colloidal matter. When the hydrolysis is substantially completed, the liquor becomes clear and the colloidal matter settles to the bottom. The liquor may become dark due to solubles in the bran, but this is ordinarily not objectionable.

The above procedures may be modified but the invention embraces modification coming within the spirit and scope of the claims. The theories, which have been developed as a result of observation and are expressed above, are presented here only for purposes of explanation and making full disclosure, and not for limitation of the invention.

The precipitation treatment with acetone, mixtures of acetone and isopropyl ether, and the like materials hereinabove described is not claimed per se herein, being covered by an application of Horace E. Hall and Robert M. Boehm, Serial No. 529,034, filed March 31, 1944.

We claim:

1. Process of treating acid solutions containing pentosans and hexosans, which comprises in-

oculating the solution with *Aspergillus niger*, allowing fermentation of the solution to go forward which selectively hydrolyzes the pentosans to pentoses and leaves the hexosans substantially unchanged, incorporating with the solution a water miscible organic solvent selected from the group consisting of acetone, ethers and lower aliphatic alcohols which precipitates the hexosans while the pentoses remain in solution, and removing the hexosans from the solution.

2. Process as defined in claim 1, and in which the acid solution is wood liquor derived from high pressure steam hydrolysis of woody lignocellulose material.

3. Process as defined in claim 1, and in which the organic solvent is added in amounts ranging from 2 to 7 volumes to 1 volume of solution. 15

4. Process as defined in claim 1, and in which the fermentation goes forward at a temperature between 50° and 60° C.

5. Process as defined in claim 1, and in which aluminum sulfate is added to accelerate precipitation of the hexosans.

6. Process of treating wood liquors containing pentosans, hexosans and a variety of impurities such as tars, acids, and lignin to separate the pentosans and hexosans from the impurities and from each other, which comprises incorporating with the wood liquor a water miscible organic solvent chosen from the group consisting of ace- 30

tone, ethers and lower aliphatic alcohols which precipitates the pentosans and hexosans, removing the precipitate from the liquor, dissolving the pentosans and hexosans in water, inoculating the water solution with *Aspergillus niger*, allowing fermentation of the solution to go forward which selectively hydrolyzes the pentosans to pentoses and leaves the hexosans substantially unchanged, incorporating with the water solution a water miscible organic solvent chosen from the group consisting of acetone, ethers and lower aliphatic alcohols which precipitates the hexosans while the pentoses remain in solution, and then removing the hexosans from the solution.
